Fig. 2.

UNITED STATES PATENT OFFICE

RUSSELL ORLANDO GROMAN, OF CATASAUQUA, PENNSYLVANIA, ASSIGNOR TO FULLER-LEHIGH COMPANY, OF FULLERTON, PENNSYLVANIA, A CORPORATION OF PENNSYLVANIA

PULVERIZER MILL

Application filed February 11, 1927. Serial No. 167,421.

This invention relates to pulverizer mills, and more particularly to mills of the air separation type in which the ground material is discharged from the grinding zone by a current of air. The invention is concerned specifically with improvements in the manner of introducing and distributing the air used for separating purposes, and also of controlling the point at which the air is introduced, whereby it is possible to regulate the fineness to which the material is ground.

The mill of the present invention may include pulverizing means of different types, but I prefer to employ the elements illustrated and disclosed in the patent to Collins, No. 1,484,298, issued February 19, 1924. In the Collins mill the grinding operation is carried on by means of a horizontal grinding ring and grinding balls which are propelled around this ring by appropriate pushing devices. The material is crushed between the balls and the ring, and lifting blades are used which are disposed above the balls and rotate with the latter, these blades causing the fine material to be thrown upwardly into the mill casing above the grinding zone. In the Collins mill the air which is used for separation purposes is introduced into the casing through a wind box and a port section which is placed adjacent to the grinding zone and extends around the casing, the air with the fine material being then discharged through a conduit which leads from the top of the mill casing to the usual cyclone separator. I have found that this method of air separation, and various others of the prior art with which I am familiar, have the disadvantage that the pressure and distribution of the air around the grinding zone is not uniform, with the consequence that the material discharged from the mill is not of uniform fineness, and thus the capacity of the mill to grind material to a selected size is considerably reduced.

The object of the present invention is to provide means for introducing air for separation purposes into the mill in such a way that the air is evenly distributed at uniform pressure around the inside of the mill casing, and particularly in the plane of the grinding zone, so that the ground material is acted on

by a uniform lifting current and thus remains in the pulverizing zone until reduced to substantially uniform size. The invention is also directed to the provision of means for controlling the action of the air used for separation purposes, so that the degree of fineness to which the material is reduced before it is discharged can be regulated as desired.

In order to accomplish the desired result the new mill includes pulverizing apparatus which operates in a horizontal plane within a casing. Above the pulverizing zone air is introduced for separation purposes into the casing, preferably at the axis of the pulverizing zone and in a downward direction. The air and fine material are removed from the casing at the top thereof in an upward direction and led to the usual separator. The air inlet and outlet ducts are preferably arranged concentric, with the outlet duct surrounding the inlet duct, so that the air flows through the casing from the inlet duct to the outlet duct to flow outwardly along radial paths. A baffle is also provided to cause the air to flow along the casing wall prior to its entrance into the outlet duct. The end of the inlet duct lies within the casing at a point normally considerably below the opening to the outlet duct, the air being thus discharged downwardly into the pulverizing zone and then returning upon itself, carrying with it the fine material and flowing into the outlet duct. The inlet duct is further provided with an adjustable end section which may be raised or lowered with reference to the pulverizing zone, and when this section is in its lowermost position, the incoming air current is discharged close to the pulverizing zone, so that it has a greater lifting effect and consequently the material being ground will be discharged more rapidly and thus will be of coarser size. When the section is placed in its uppermost position, the material discharged from the mill will be as fine as the grinding apparatus is capable of producing. In intermediate positions the size of the material being discharged will vary in accordance with the position of the section, and will become coarser as the section is lowered.

For a better understanding of the inven-

tion, reference may be had to the accompanying drawings, in which

Fig. 1 is a view inside elevation and partly in section, showing the improved mill construction, and

Fig. 2 is a top plan view thereof.

Referring now to the drawings, the mill is illustrated as mounted on a suitable bed 20 of concrete or other like material, and it includes a base section 21 to the bottom of which is connected the casing 22 for the driving mechanism. In this casing is the lower bearing 23 for the vertical shaft 24 and also a bearing 25 for the drive shaft 26. The drive shaft 26 is coupled to the shaft 27 of a driving motor 28 mounted at any convenient point. The shaft 26 is supported in a bearing 29 of any suitable construction and carries a beveled gear 30, meshing with a similar gear 31 on the vertical shaft 24. The vertical shaft carries at its upper end a yoke 32 provided with pushing devices, not illustrated, for propelling the balls 33 which, in the operation of the mill, run in the grooved face of a grinding ring 34 mounted in the section 21. The yoke 32 carries lifting blades 35 of suitable form, these blades being inclined so as to cause the material being ground to be raised from the grinding zone as the yoke is rotated. The details of the pulverizing and lifting apparatus may vary within wide limits and as these parts are well-known in the art, a detailed description of them is not necessary.

Above the base section 21 is mounted a casing section 36 carrying a casing 37 provided with a feeder extension 38 through which the material to be ground may be introduced into the pulverizing zone. The casing terminates at its upper end in a neck 39 in which is mounted an outlet duct 40 leading into an air separator 42 of any convenient form, here illustrated as being of the well-known cyclone type and having a lower discharge end 42' for the material. The air outlet pipe has a section 43 which projects into the casing below the neck 39 and lies clear of the walls of the casing.

A duct 44 serving as the outlet for air from the separator, leads the air back into the mill casing, the duct 44 having a portion which enters the wall of the outlet duct 40 and terminates in an end section 45 which projects into the casing beyond the end 43 of the outlet duct. The inlet and outlet ducts are concentric and the inlet duct is also substantially concentric with the shaft 24, that is, with the axis of the rotating pulverizing elements.

The air discharged from the lower end of the inlet duct into the mill casing passes down into the pulverizing zone and flows across the zone along radial paths to the outer wall of the casing, being there deflected upwardly along that wall, as indicated by the

arrows. Secured to the lower end of the outlet pipe by straps 46, or in any other convenient manner, is a fixed baffle 47 in the form of an inverted, truncated cone. This baffle surrounds the lower end 45 of the air inlet duct, and is spaced from it. Owing to the shape and position of the baffle, the air flowing upwardly along the outer casing wall and carrying with it the fine material passes over the top outer edge of the baffle, then turns downwardly slightly, and finally again turns upwardly to flow into the duct to the air separator. In this change of direction the heavier particles carried by the air are precipitated and may fall on the inner surface of the baffle, escaping from the lower end of the latter, the edge of the baffle at this end being spaced from the end of the inlet duct. The manner of introducing the air into the pulverizing zone at the axis thereof and withdrawing it as described results in an even distribution of the air throughout the entire mill casing, and the air pressure within the casing is also uniform. Thus all the particles which are being ground are acted on by air of uniform pressure and velocity, and consequently the particles which are lifted by the current are all of substantially the same size.

In order to control the lifting effect of the air, the end section 45 of the inlet duct is mounted for vertical adjustment, being carried on rods 48 which extend radially from the section and are then turned upwardly at right angles and pass through adjusting devices 49 in the wall of the casing. By moving the section 45 upwardly or downwardly, coarse or fine particles may be discharged from the mill. When the section is in its lowermost position of adjustment, the air current is introduced into the casing at a point close to the pulverizing zone, and thus exercises a great lifting effect, capable of causing the removal of coarse particles from the zone. When the section is in its uppermost position of adjustment, the air is discharged into the casing at a point considerably above the zone, and thus more of the air has an opportunity to pass across the casing to its outer walls without entering the zone. The air current under these conditions has a less lifting effect and the section is so constructed that in its uppermost position the material which is discharged is as fine as the mill is capable of producing. By adjustment of the end section of the air inlet duct to intermediate positions, the size of the particles which are discharged from the mill may be varied, but with any position of adjustment substantially all the particles which are discharged from the mill are of the same size, owing to the uniform air distribution within the casing.

It will thus be seen that the new mill is more efficient than those which have heretofore been constructed, because of the uniform-

ity of the ground product which is discharged, due to the more even distribution of the air current. Furthermore, the new mill provides a convenient means for controlling the operation of the grinding elements so that grinding to different degrees of fineness may readily be carried on simply by adjusting the air flow.

I claim:

1. In a pulverizer mill, which includes pulverizing elements, the combination of a casing at one end of which said elements are disposed, an air inlet duct entering the casing at its opposite end for introducing air into the casing above the elements and in a downward direction, an air outlet duct at the said end of the casing surrounding and concentric with the air inlet duct for the outward flow of air from the casing in an upward direction, a baffle of inverted truncated form mounted within the casing in the path of air flowing into the outlet duct and causing the air to flow along the casing wall prior to its entrance into the said outlet duct, and a vertically adjustable end section for the air inlet duct movable to different positions of adjustment with reference to the elements to vary the point at which air is admitted into the casing, this end section being movable through the baffle.

2. In a pulverizer mill which includes a power driven pulverizer unit, the combination of a closed stationary casing disposed above and open to the unit, this casing forming an integral part of the mill, an air inlet duct entering the casing wall at a point remote from the unit for delivering air into the casing above the unit, and an air outlet duct entering the casing wall adjacent said air inlet ducts and permitting the flow of air from the casing, those portions of the ducts within the casing being concentric and so arranged that the flow of air from the inlet duct to the outlet duct within the casing is partly along horizontal, radial paths.

3. In a pulverizer mill which includes a power driven pulverizer unit, the combination of a stationary closed casing disposed above and open to the unit, this casing forming an integral part of the mill, an air inlet duct entering the wall of the casing for delivering air into the casing above the unit and in a downward direction toward said unit, and an air outlet duct entering the casing wall to permit the flow of air from the casing in an upward direction, the portions of these ducts within the casing being concentric and so arranged that the flow of air through the casing between the inlet and outlet ducts is partly along horizontal, radial paths.

4. In a pulverizer mill which includes a power driven pulverizer unit, the combination of a closed casing above and in communication with the unit and forming an integral part of the mill, an air inlet duct

entering the casing wall at a point remote from the unit for delivering air into the casing above the unit, an air outlet duct entering the casing wall and permitting the flow of air from the casing, those parts of the ducts within the casing being concentric, and baffle means within the casing for causing the air flowing between the inlet and outlet duct openings to flow along the outer wall of the casing before it enters the outlet duct.

5. In a pulverizer mill which includes a power driven pulverizer unit, the combination of a closed stationary casing forming an integral part of the mill and disposed above and open to the unit, and air inlet duct entering the casing wall at a point remote from the unit for delivering air into the casing above the unit and in a downward direction toward it, and an air outlet duct entering the casing wall and permitting the flow of air from the casing in an upward direction, the portions of the ducts within the casing being concentric with the outlet duct surrounding the inlet duct, the axis of the inlet duct being co-incident with the axis of the pulverizer unit.

6. In a pulverizer mill which includes a power driven pulverizer unit, the combination of a casing forming an integral part of the mill and disposed above and open to the unit, an air inlet duct entering the casing wall for delivering air into the casing above the unit and in a downward direction toward it, this inlet duct having an adjustable end section within the casing by means of which the point of delivery of the air into the casing with reference to the unit may be varied, and an air outlet duct entering the casing wall for the upward and outward flow of air from the casing, the portions of the ducts within the casing being concentric.

7. In a pulverizer mill which includes a power-driven pulverizer unit, the combination of a stationary closed casing forming an integral part of the mill and lying above and open to the unit, an inlet duct entering the casing wall for delivering air into the casing above the unit and in a downward direction toward it, this duct having an adjustable end section by which the point of delivery of the air into the casing may be varied, and an air outlet duct entering the casing wall for the upward and outward flow of air from the casing, the portions of these ducts within the casing being concentric and the end sections of the inlet duct normally lying below the end of the outlet duct.

8. In a pulverizer mill which includes power-driven rotary pulverizer elements, the combination of a closed casing forming an integral part of the mill and lying above said elements, an air inlet duct extending downwardly through the top wall of the casing for delivering air above the pulverizer elements, this duct being disposed with its axis coinci-

dent with the axis of the elements, an air outlet duct entering the casing wall, the portions of these ducts within the casing being concentric, and baffle means in front of the opening to the air outlet duct arranged to cause the air to flow upwardly along the casing wall prior to its entrance into the outlet duct.

9. In a pulverizer mill which includes power-driven pulverizer elements, the combination of a closed casing disposed above and open to said elements, this casing forming an integral part of the mill, an air inlet duct entering the casing wall for delivering air into the casing above the pulverizer elements, this duct having an end section capable of adjustment to vary the point of delivery of the air into the casing, an air outlet duct entering the casing wall for the flow of air from the casing and arranged concentric with the inlet duct, and baffle means in the path of the air entering the outlet duct and causing the flow of air along the walls of the casing prior to its entrance into the outlet duct.

25 10. In a pulverizer mill which includes power-driven pulverizer elements, the combination of a closed casing forming an integral part of the mill and lying above the elements and open thereto, an air inlet duct 30 extending downwardly through the top wall of the casing for delivering air above the pulverizer elements, this duct being disposed with its axis coincident with the axis of the elements, an air outlet duct entering the casing wall and surrounding the inlet duct and concentric therewith, an adjustable end section for the inlet duct capable of vertical adjustment to vary the point of delivery of the air into the casing with reference to the pulverizer elements, and a baffle disposed within the casing in the path of the air flowing into the outlet duct, the inlet duct and the baffle cooperating to cause the air to flow across the casing in radial paths, then upwardly along the casing walls to the air outlet.

45 11. In a pulverizer mill which includes a power-driven pulverizer unit, the combination of a closed casing disposed above and open to the unit, this casing forming an integral part of the mill, a single air inlet duct 50 entering the casing wall for admitting air into the casing in a downward direction above the unit and in an extension of the axis thereof, an air outlet duct for the flow of air from the casing, this outlet duct being concentric with the inlet duct, and the ducts cooperating so that air introduced into the casing flows into the unit and across the latter along radial paths, then upwardly along the casing walls to the outlet.

55 12. In a pulverizer mill which includes rotary pulverizer elements operating in a horizontal plane, the combination of a casing above and open to said elements, this casing being closed and forming an integral part

of the mill, an air inlet duct entering the casing wall for delivering air into the casing in a downward direction along the axis of the elements, an air outlet duct entering the casing wall and surrounding and concentric with the inlet duct for the flow of air outwardly from the casing in an upward direction, an end section for the air inlet duct mounted for vertical adjustment whereby the point of admission of the air into the casing may be varied with reference to the plane of the pulverizer elements, and baffle means in the casing in the path of the air entering the outlet duct, the end section and the baffle means cooperating to cause the air to flow downward into the pulverizing zone, across the latter in radial paths, then upwardly along the casing wall to the outlet duct.

70 13. In a pulverizer mill which includes a pulverizer unit, the combination of a closed casing disposed above and open to the unit, this casing forming an integral part of the mill, an air inlet duct entering the casing wall for introducing the air into the casing above the unit, an air outlet duct entering the casing wall with its portion within the casing concentric with the inlet duct for the outward flow of air from the casing, a separator remote from the mill and connected to the outlet duct, an outlet from the separator connected to the air inlet duct, and a power-driven fan for causing the continuous circulation of air through the casing and the separator.

75 80 85 90 95 In testimony whereof I affix my signature.
RUSSELL ORLANDO GROMAN.
